(57) **CLAIM**

I claim the ornamental design for baluster of a gate for feeding cattle, as shown and described.

DESCRIPTION

FIG. 1 is a front elevation view of a baluster of a gate for feeding cattle, the rear being identical thereto;

FIG. 2 is a left side elevation view thereof, the right side being identical thereto;

FIG. 3 is a top plan view thereof;

FIG. 4 is a rear elevation view of a second embodiment of a baluster of a gate for feeding cattle;

FIG. 5 is a left side elevation view thereof, the right side being identical thereto; and,

FIG. 6 is a top plan view thereof.
